UNITED STATES PATENT OFFICE.

JENNIE G. MORLEY, OF BUFFALO, NEW YORK.

DESIGN FOR AN ABDOMINAL SUPPORTER.

SPECIFICATION forming part of Design No. 29,163, dated August 2, 1898.

Application filed December 9, 1897. Serial No. 661,328. Term of patent 14 years.

To all whom it may concern:

Be it known that I, JENNIE G. MORLEY, a citizen of the United States, residing at Buffalo, in the county of Erie and State of New

5 York, have invented and produced a new and original Design for Abdominal Supporters, of which the following is a specification, reference being had to the accompanying drawings, forming a part thereof.

- o This design consists of the configuration of the lower portion of an abdominal supporter of the kind which is composed of a front and a rear section joined at the sides and having the rear section provided with buttock-flaps.
- 5 In the accompanying drawings, Figure 1 is a side elevation of an abdominal supporter embodying my design. Fig. 2 is a rear view thereof. Fig. 3 is a front view of the same.

Like letters of reference refer to like parts of the several figures.

The characteristic feature of my design consists of the form of the lower outline of the supporter, which consists of rounded or curved scallops rising on each side from the tip or tongue of the front section to the junction of the front and rear sections, then descending to the lower end of each buttock-flap, and then rising again in the rear to the highest point of the central recess between

10 the buttock-flaps.

A represents the front or abdominal section of the supporter; a, the tip or tongue thereof;

a' , the contracted side portion, and a^2 the lower curved edge rising from the tip or tongue a to the rear edge of the side portion. 35

a^3 represents upright strips on the front section.

B represents the rear section, and b the buttock-flaps. The contracted side portions b' of the rear section are joined to the front 40 section on each side at d. The lower edge of the rear section descends from each line of junction, as shown at b^2 , to and along the lower edge of each buttock-section and then up to and along a recess c, formed centrally in the 45 rear section between the buttock-flaps, so that the lower edge of the supporter has the form of rounded scallops, particularly on the rear side.

b^3 b^4 represent upright strips on the buttock-flaps, and Cupright strips on the central portion of the rear section. 50

e represents straps or cords connecting the tongue of the front section with the buttock-flaps. 55

What I claim is—

The design for an abdominal supporter, substantially as herein shown and described.

Witness my hand this 30th day of November, 1897.

JENNIE G. MORLEY.
